SAFETY FEEDING SPOON FOR INFANTS

Albert Bloom, Hicksville, N. Y.

Application January 2, 1958, Serial No. 49,092

Term of patent 14 years

(Cl. D54—12)

Fig. 1 is a plan view of a safety feeding spoon for infants showing my new design; and

Fig. 2 is an elevational view of the spoon shown in Fig. 1.

The back of the spoon is conventionally plain in appearance.

I claim:

The ornamental design for a safety feeding spoon for infants, as shown and described.
